(57) CLAIM

The ornamental design for a sole for footwear, as shown and described.

DESCRIPTION

The file of this patent contains at least one drawing/photograph executed in color. Copies of this patent with color drawings/photographs will be provided by the Office upon request and payment of the necessary fee.

1. Sole for footwear

1.1 : Left

1.2 : Front

1.3 : Back

1.4 : Bottom

1.5 : Right

Outer sole for footwear displaying a bottom surface and elevated lateral portions in orange color.

1 Claim, 5 Drawing Sheets
(5 of 5 Drawing Sheet(s) Filed in Color)
